UNITED STATES PATENT OFFICE.

JOHN LAWSON, OF CENTRAL FALLS, RHODE ISLAND, ASSIGNOR, BY MESNE ASSIGNMENTS, TO HEMPHILL COMPANY, OF CENTRAL FALLS, RHODE ISLAND, A CORPORATION OF MASSACHUSETTS.

AUTOMATIC TENSION-CONTROLLING MEANS FOR KNITTING MACHINES.

1,424,025.

Specification of Letters Patent. Patented July 25, 1922.

Application filed March 2, 1914. Serial No. 821,867.

To all whom it may concern:

Be it known that I, JOHN LAWSON, a citizen of the United States, residing at Central Falls, in the county of Providence and State of Rhode Island, have invented certain new and useful Improvements in Automatic Tension-Controlling Means for Knitting Machines, of which the following is a specification.

- 10 This invention relates more particularly to hosiery knitting-machines of the full automatic type, an example of which is disclosed in U. S. Patent No. 933,443, issued to J. D. Hemphill, Sept. 7th, 1909.
- 15 The improvement forming the subject of the present application for patent resides in new and improved means for automatically controlling in an independent manner the degree of tension and slack of each of a plurality of knitting-threads. In other words, the object of the invention is to provide a knitting-machine with a plurality of adjustable independently arranged devices, one for each knitting-thread, adapted to become mechanically operable at certain pre-arranged parts in the production of the stocking, whereby the normal tension on the active knitting-threads is automatically relieved when the threads are inactive.
- 20 The invention includes in its construction a series of suitably arranged and timed independently controlled cams (one cam for each knitting-thread), a corresponding series of spring-pressed members, each controlled by its relatively positioned cam, and brake members normally disengaged from the respective threads when one or more of the latter are in normal knitting action. Conversely, the mechanism acts automatically to release the tension from each of the inactive threads held under the binder device.
- 25
- 30
- 35
- 40

By means of my invention the device is also adapted to automatically take up the slack of the respective active threads when the knitting-machine is being rotated in a reciprocatory manner, as for example during the knitting of the high-splice split-foot heel and toe portions of the stocking.

In the accompanying sheet of drawings, 50 Figure 1 represents a partial side elevation illustrating my improvement as applied to a rotary-cylinder type of hosiery knitting-machine, only portions of the latter being shown; the position and relative arrange-

ment of the parts correspond substantially with regular or normal circular knitting. Fig. 2 is a corresponding top plan view, some of the parts, however, being omitted. Fig. 3 is a detached front end elevation of the main bracket or base showing portions of my improved tension controlling device. Fig. 4 is a partial side view of the take-up controlling means proper; in this figure one of the take-up members of the series is represented as temporarily engaging and yielding holding the active thread while it is being converted into stitches, the cylinder (not shown in the figure) meanwhile moving in a reciprocatory manner; and Fig. 5 is a top plan view, in reduced scale, showing the latch-ring, thread binder, portions of the bobbin-stand rod, etc.

The drawings represent improved means for automatically controlling the take-up and release of the individual knitting-threads at certain points in the knitting operation, whereby a more uniform degree of tension is imparted to the threads during the production of the knitted web.

The needle-cylinder N is or may be provided with the usual devices and accessories for producing knitted work and is further provided with a swinging latch-ring L hinged to a standard L'; to the said member L, and angularly movable bodily with it, is attached a thread-binder d' and cutter d'', arranged centrally of the needle-cylinder.—see Fig. 5. I make no claim herewith to the cutter and binder-devices nor to means for operating them.

Positioned above the cylinder N is located a supported disk n provided with a plurality of guide eyes e', through which eyes the several knitting-threads t extend downward to engage the said binder and needles in a well known way. The machine is provided with a horizontally mounted pattern or main cam-shaft s' to which latter cams may be secured for actuating certain of the knitting devices; the rotary movements of the shaft 100 being effected in a step-by-step or intermittent manner; one revolution of the shaft corresponding to the production of the knitted unit or stocking.

At the rear side of the machine is mounted a vertically extending bobbin stand rod R to which is secured the hub a of the upper take-up bracket A, the latter being in aline-

ment with the lower bracket h^4 , also adjustably fixed to the rod. The bracket A extends horizontally in front toward the center of the needle-cylinder and is provided at its front end a^1 with a number of thread-guiding eyes, e^1 , four being represented, one for each of the said eyes e^1 of the member n below.

At the opposite end portion of bracket A are located in its flange b a corresponding number of spaced eyes or guides e alining substantially with corresponding eyes e^1 , e^2 arranged to receive the respective knitting threads t leading from the bobbins. At a point above the eyes e^1 the bracket is provided with a horizontally mounted transverse short shaft f^1 fixed to a member a^2 of the bracket, on which shaft a series of four hubs f are mounted for independent swinging movement, each carrying a light, wire finger F having its front portion f^2 bent downwardly at substantially right angles and terminating in a guide-eye f^4 . Each member f has a rearward flange f^2 arranged to be engaged by the front end c^1 of a weight-arm or lever c pivoted at b^1 to said flange b ; the lever member c has a downward extension c^2 arranged when the lever is unsupported by the part f^2 , to drop from the latter by gravity and frictionally engage its thread t lying on the upper face e^3 , thereby holding the thread in check and subjecting it to yielding tension while the cylinder is producing reciprocatory knitting. See corresponding position of parts represented in Fig. 4.

Means normally acting to relieve the tension from the inactive thread or threads are represented in the corresponding position shown in Fig. 1. That is to say, a series of four cams i (one only being shown) are adjustably secured to the intermittently movable cam-shaft or pattern-shaft s^1 , each cam having, say a plurality of suitably arranged concentric raised lugs i^1 alternating with plain concentric peripheral depressions i^2 ; these surfaces of the cams are in engagement with the outer front ends r of the respective actuator-levers D , pivoted to swing on a stud j , fixed say to the frame of the machine. The rear end of each lever D is jointed to a wire rod h extending freely vertically therefrom through guide bearings formed in the bracket h^4 and the hub b^2 of said bracket A, the latter being positioned a distance above the member h^4 . A light spring h^3 is interposed between the bracket h^4 and a collar h^1 , the latter being adjustably secured to the rod h by a set-screw h^2 , whereby the degree of the spring's pressure may be varied as desired; the normal action of the spring h^3 operates to keep the end r of lever D in continuous yielding engagement with the said cam surfaces.

To the upper portion of each rod h is ad-

justably secured, by means of a screw s^2 , what may be termed a controller member B, having its free end s enlarged and bent downwardly. In normal circular knitting the engagement of the respective levers D with the raised portions i^1 of the corresponding cam i operates to maintain the end s of the controller in engagement with the finger F, thereby locking the latter in depressed position; the device acts to automatically swing the brake lever c upward to disengage its clamping portion c^2 from the thread t , see Fig. 1. It will be seen that the hub f of the thread-carrying finger F is yieldingly attached to a vertical spring-like connection k adjustably secured to the lower bracket h^4 by means of a screw k^1 . When, however, the lever D engages the depressed portion i^2 of the cam the spring-pressed rod h and its attached controller B are caused to move upward, the movement at the same time automatically releasing the finger F and permitting spring k to swing it upward also, this movement of the finger acts to automatically release the lever c from flange f^2 , whereby the last named lever in falling causes its portion c^2 to engage and clamp the thread thereunder. See corresponding position Fig. 4. The rods h have rectilinear movement and impose such movement upon the controller members B.

As thus constructed and arranged the tension or pull on the thread passing through the eye or guide f^4 at the free end of the swinging finger, when reciprocatory knitting is being produced, is practically even or uniform, the device serving not only to take up the slack portion of the thread during each reciprocatory stroke, but also producing a more uniform degree of tension throughout the stitches of the courses of reciprocatory knitting.

The bracket A may be additionally provided at its front end with an auxiliary tension device H, of well-known construction, shown most clearly in Figs. 1 and 3, to which are attached a plurality of light, resilient vertical members m , through which latter freely pass pins or screws v having springs v^1 pressing lightly against the said parts m , the arrangement being such that the threads t are capable of passing with a slight degree of resistance between the adjacent faces of the parts v and m , so as to be drawn smoothly therefrom through the guide-eyes f^4 , e^3 and e^1 to the needles.

When plain circular knitting is being produced the active thread of the corresponding thread-carrying finger F is relieved of the auxiliary or brake pressure imposed upon it (the active thread), said finger then being in the depressed position by means of the correspondingly depressed position by means of the correspondingly depressed arm B, as indicated in Figure 1 by full lines; at

the same time the then inactive or idle threads of the other fingers of the series are caused to be swung upwardly by the reaction of the spring connections *k* immediately following the release of the arms *B* from the fingers, thereby permitting the brake *c* to automatically engage the inactive threads and increase the tension upon them, and hold them practically stationary. The dotted lines in Figure 1 indicate in general the position of the parts controlling said idle threads while the said active thread is being knitted. In order to more clearly represent the corresponding position of the mechanism controlling said idle threads the same is shown in the detached Figure 4.

When reciprocatory knitting is to be produced, as for example in forming the heel and toe portions of a stocking, and also in high-splicing, certain of the cams *i* are pre-adjusted to release the arm *B* from the finger *F* carrying the active knitting-thread, and having the other fingers, with the then idle threads threaded therein, temporarily held downward substantially as indicated by full lines in Figure 1. At each reciprocation of the needle-cylinder the excess thread or slack drawn off both in narrowing and widening is automatically taken up by the spring-connected swinging finger *F* carrying the said active thread; the connection *k* serves to maintain a more uniform pressure or tension on the thread while at the same time the action of the swinging finger acts to take up the slack thread in a more uniform manner.

It is to be observed that the usual means for feeding or introducing the active threads to the needles through the medium of yarn-levers, as *d*, Figure 5, at the proper point are not necessarily altered or changed by the employment of the improvement, nor in fact are the functions of the binder arm *d¹* and thread-severing means *d²*, indicated in said Figure 5.

With the construction shown and described, the position of each of the several take-ups employed, and consequently of each of the tension devices controlled thereby, is independently determined or controlled. By reason of this fact a portion of said take-ups, one or more, may be in operative position, while the remainder are held in inoperative position. This is an important advantage, as for example in knitting what

are known as split foot stockings, in which two yarns are employed in the reciprocating action of the machine in knitting the split foot, requiring two of the take-ups to be in operative position and operating to take care of the two yarns being knit. In knitting the heel and toe of such stocking one or two other yarns may be and frequently are employed, and when the heel or toe is being knit the take-ups for these other yarns will be in operative position while the take-ups for the two yarns employed in knitting the split foot may be held in inoperative position.

I claim:

A circular knitting machine having in combination a plurality of guides for a corresponding plurality of threads, a corresponding plurality of take-ups, and a corresponding plurality of pivoted tension devices, one for each of said threads, each take-up and its corresponding tension device being structurally distinct and independent from all the other said take-ups and tension devices, and each pivoted tension device having a part to be engaged by the corresponding take-up, thereby to render the same active or inactive, a cam shaft, means thereon having a corresponding plurality of cam elevations and depressions, said elevations and depressions controlling the position of the corresponding take-up and tension device for circular work and the position of the take-ups and tension devices for reciprocating work, a corresponding plurality of levers adapted to engage said cam elevations and depressions respectively, link like members extending upwardly from said levers and having rectilinear movement, a controller member carried by each of said link like members and movable therewith, and a separate spring to act on each controller member, each of said controller members being structurally free from but adapted periodically to be brought into pushing contact with its take-up to depress the same and to release the corresponding tension device.

In testimony whereof I have affixed my signature in presence of two witnesses.

JOHN LAWSON.
